CABINET OR SIMILAR ARTICLE

Thomas J. Stepwith, 16704 Marquis Ave.,
Cleveland, Ohio 44111

Filed Mar. 26, 1968, Ser. No. 11,142

Term of patent 14 years

Int. Cl. D6—01

U.S. Cl. D33—19

FIG. 1

FIG. 2

FIG. 3

FIG. 1 is a perspective view of my new design for a cabinet or similar article.

FIG. 2 is a side elevational view of my new design.

FIG. 3 is a top view of my new design.

The side not shown is like the side shown while the back is plain and unornamental.

I claim:

The ornamental design for a cabinet or similar article, substantially as shown and described.
